PORABLE WORK LAMP

Jay Monroe, Flushing, N.Y., assignor to Tensor Electric Development Co., Inc., Brooklyn, N.Y., a corporation of New York

Filed July 19, 1961, Ser. No. 65,975

Term of patent 14 years

(Cl. D48—20)

FIG. 2.

FIG. 3.

FIG. 1 is a front perspective view of a portable work lamp showing my new design;

FIG. 2 is a side elevation thereof; and

FIG. 3 is a rear elevation thereof.

I claim:

The ornamental design for a portable work lamp, as shown.
